UNITED STATES PATENT OFFICE.

WINFRED T. POWELL, OF ROCHESTER, NEW YORK, ASSIGNOR TO THE STROMBERG-CARLSON TELEPHONE MANUFACTURING COMPANY, OF ROCHESTER, NEW YORK, A CORPORATION OF NEW YORK.

CALL-DISTRIBUTING SYSTEM.

Application filed March 31, 1920. Serial No. 370,142.

This invention relates to telephone systems, and more particularly to telephone systems in which automatic switches are employed to distribute calls to various operators.

In manual telephone systems of relatively large size it is necessary in the case of certain calls that the connection be completed through two or more offices. In accordance 10 with the practice formerly employed, for such cases a so-called order wire extending between the two offices serves as a means over which the operator at the first office, known as the A operator, was able to repeat 15 the wanted number to the operator at the second office who is known as the B operator.

Briefly the operation of extending a call in such a manual system, involves the connection of the answering end of the A operator's 20 cord circuit to the calling line, and this operator receives the designation of the wanted line. She thereupon instructs a B operator at the wanted office of the number 25 of the wanted line over an order wire, and the B operator instructs the A operator over the same order wire of the number of the trunk to be used. The A operator then inserts the calling end of the cord circuit into 30 the jack of the trunk circuit designated.

In the present invention the order wire has been omitted and in its stead a series of trunks and automatic switches are employed. In the present system on the initiation of a 35 call the A operator inserts the answering end of her cord circuit into the jack of the calling line and receives the designation of the wanted line. She thereupon inserts the calling end of her cord circuit into any one 40 of a plurality of jacks of trunks leading to the wanted office. A trunk selecting switch then selects an idle trunk leading to the wanted office where primary and secondary switches select idle trunks to connect the 45 calling line to a B operator's position. While these switching operations are taking place, a tone is transmitted to the A operator's telephone set to inform her that the B operator is not in readiness to receive the 50 call. When, however, the tone is discon-

tinued, the A operator repeats the designation of the wanted line and the B operator after testing the wanted line and finding it idle, inserts the calling end of her cord circuit into the jack of the wanted line. The 55 signaling of the wanted line and the other operations then take place.

Where primary and secondary switches are used, it becomes necessary to prevent a primary switch from seizing a secondary 60 switch whenever all the trunks leading from a secondary switch are in use.

One of the main features of the present invention is the provision of means to prevent the primary switches from seizing a 65 secondary switch when all outgoing trunks from the secondary switch are engaged.

Other features of the invention will appear from the detailed description and claims.

The drawings with Fig. 2 placed at the right of Fig. 1 diagrammatically represent a telephone system having one or more B operators' positions and in which a predetermined number of calls are apportioned to 75 each B operator's position, and when this predetermined number of calls are unanswered at this B position no other calls can be extended thereto. In Fig. 1 there is 80 diagrammatically represented an office designated #1 and part of a second office #2. In office #1 there is represented a calling subscriber's line and its associated equipment. A cord circuit at the A operator's position is also indicated, and the circuits 85 of the trunk selecting switch for selecting an idle trunk to a wanted office are shown at the left of the dotted line. At the right of the dotted line there is shown the equipment of office #2 for selecting an idle B 90 operator's position. In Fig. 2 there is shown one plug ended trunk circuit individual to this position, as well as other equipment below the dotted line common to all trunk circuits of this position. At the upper right 95 hand corner of Fig. 2 there is shown a telephone line, herein referred to as the called line. Figs. 2^A and 3 when substituted for Fig. 2, represent a modified form of the invention, in which overflow positions are 100

shown. As many of these positions will be provided as are necessary to care for traffic which cannot be handled by the regular B operators' positions. Corresponding parts 5 of Fig. 2^a are designated by the same reference characters as are used in Fig. 2.

The switches of the present invention may be of the structure substantially similar to that disclosed in the patent to Clement, 10 #1,107,153, patented August 11, 1914.

It will be understood that the equipment of office #1, such as the operator's cord circuit as well as the operator's telephone set, will be of the character of these now in use 15 in manual common battery telephone systems.

Several of the relays, notably 10, 25 and 20 33 have contacts designated X which indicates that these contacts close before other contacts on the associated relay are operated.

It is believed the invention will best be understood by describing the method of extending a call from a calling substation, 25 such as A to a called substation such as B, and subsequently explaining the method of extending the calling line to a second called substation, such as C.

When the calling subscriber at A initiates 30 a call by removing his receiver from its switchhook, the line relay LR individual to his line, is energized over a circuit controlled at back contacts of the cut-off relay CO, and this relay is actuated to light the lamp 5 associated with the answering jack 6 of the calling line. The operator on noting that lamp 5 is lighted, inserts her answering plug 7 into the jack 6. This operation causes the 35 cut-off relay CO to be energized, which de-energizes the line relay LR, which in turn extinguishes the lamp 5. The operator thereupon depresses her listening key LK which connects her telephone set in bridge of the answering end of her cord circuit and ascertains from the calling party the designation 40 of the wanted office and the desired line terminating thereat. The operator then inserts the calling plug 8 of the cord circuit which she has taken for use into one of a group of 45 jacks 9, through which the wanted office may be reached. As soon as the plug 8 is inserted into the jack 9, the relay 10 is energized in a circuit closed from ground, winding of the 50 relay 10, sleeve of the jack 9, sleeve of the plug 8, winding of relay 11 which controls a supervisory relay (not shown) to grounded battery. The relay 10 attracts its armatures, and at its middle armature connects a tone 55 over conductor 12, inner-most upper back contact and armature of relay 13, through the lower side of the cord circuit, the operator's telephone set, upper side of the cord circuit to ground, through the supervisory relay 14. This tone or a similar tone will be 60 applied to the A operator's headset until the

B operator is ready to receive the designation of the wanted line.

At the inner-most armature of relay 10, a circuit is closed from grounded battery, resistance, winding, armature and back contact of the motor magnet 15 of the distributor switch, lower back contact and armature of relay 13, inner-most front contact and armature of relay 10 to ground. Under the control of this circuit, the distributor switch 75 advances its brushes progressively until its test brush 16 encounters the test terminal of an idle trunk leading to the wanted office. This idle condition is indicated by the presence of ground potential on its test terminal. 80

Let it be assumed that the first idle trunk circuit tested by the distributor switch is the one whose conductors are designated 17 and 18 in Fig. 1. As soon as this trunk is tested, a circuit is completed from ground, outer armature and back contact of relay 19, test terminal of this trunk, test brush 16, upper winding of relay 13 which has low resistance, outer-most front contact and armature of relay 10, resistance, to grounded battery. 90 This circuit shunts the stepping magnet 15 of the distributor switch to stop the same and also energizes the switching relay 13. This last named relay attracts its armatures, and at its lower armature and front contact 95 closes a holding circuit for itself through its high resistance winding, from ground, inner-most armature and front contact of relay 10, armature, front contact and winding of relay 13, holding brush 20, over the holding terminal of the selected trunk and winding of relay 19 to grounded battery. At the upper armatures of the switching relay 13, the calling line is extended to the wanted office. At the outer armature and back contact of relay 19, a guarding condition is placed on the test terminal of the selected trunk. At the inner front contact and armature of relay 19, a break point in the conductor 21 is closed. This conductor 21 extends a circuit for relay 22, but this relay is short circuited by ground at the armatures and back contacts of relays similar to 19 associated with idle trunks of the group. However, as soon as all the trunks of the group are engaged, 110 these various shunting circuits are removed and the relay 22 attracts its armatures to control the operation of the meter 23 and of a visual signal 24 at the position to notify the A operator that all the outgoing trunks 115 of a particular group are in use. As soon as the conductors 17 and 18 of the selected trunk are extended to the wanted office, relay 25 is operated in a circuit traceable from grounded battery, left hand winding of this 120 relay, upper-most back contact and armature of relay 26 to ground, through the winding of the relay 14 of the A operator's cord circuit. At the left hand armature and front contact of relay 25 a tone is extended over 125 130

conductor 27. This second tone is applied to the A operator's headset as soon as the first tone is removed so she will know that the B operator is not ready to receive the wanted 5 number. At the outer-most armature and front contact of relay 25 a circuit is closed from ground, back contact, armature and winding of the motor magnet 28 of a distributor switch which will be designated a primary 10 switch, resistance, to grounded battery. Under the control of the motor magnet 28, this primary switch advances its brushes until its test brush 29 encounters the test terminal of an idle trunk.

15 Let it be assumed that the trunk whose conductors are designated 30 and 31 is the first idle trunk tested. A circuit will thereupon be closed from grounded battery, resistance, inner armature, front contact and 20 winding of relay 25, upper winding of relay 26, test brush 29, conductor 32, outer left hand armature and front contact of relay 33 to ground at the armatures and back contacts of a "group-busy" relay 34 to stop the 25 primary switch and operate relay 26. As soon as the relay 26 attracts its armatures, it closes a holding circuit for itself from ground, its lower winding, lower armature and front contact, holding brush 35, winding 30 of relay 33 to grounded battery. As soon as the relay 33 is operated, it extends a tone to the A operator's headset over conductor 36 and its inner left hand contact and armature, and at its outer left hand armature 35 applies a busy condition to the selected 40 trunk. At the outer right hand armature and front contact of relay 33, a circuit is closed from ground, lower-most armature and back contact of relay 37, armature, back 45 contact and winding of the motor magnet 38, resistance, to grounded battery. Under the control of this motor magnet, the secondary distributor switch herein called the secondary switch advances its brushes to find 50 an idle trunk circuit leading to a final connecting operator. The idle condition of the trunk will be indicated by the presence of ground on its test terminal applied over conductor 58 and controlled at the outer right 55 hand front contact and armature of relay 69, so that when the test brush 41 encounters an idle test terminal a circuit will be closed through the lower winding of relay 37, innermost right hand front contact and armature 60 of relay 33, resistance, to grounded battery. This circuit energizes the relay 37 and shunts the motor magnet 38 to stop the secondary switch. Relay 37 when energized, closes a locking circuit from grounded battery, its upper winding, lower-most front 65 contact and armature, outer-most right hand front contact and armature of relay 33 to ground. At its upper armatures and front contact the A operator's telephone set is connected to a trunk circuit terminating in

a plug at a B operator's position. At the upper back contact and armature of relay 37, the tone is no longer communicated to the A operator's headset, thus informing her that the B operator is now ready to receive 70 the wanted number. As soon as the last mentioned trunk is seized, its relay 42 is energized over a holding brush 43, innermost lower front contact and armature of relay 37, holding brush 35, lower front contact, armature and winding of relay 26 to ground. A relay similar to 42 is provided for each trunk of the group to which the secondary distributor switch has access. As soon as the A operator's cord circuit has 80 been extended over the trunk conductors 43 and 44, the relay 45 of Fig. 2 is energized over the two sides of the link circuit and operator's cord circuit in series, through the winding of relay 14 to ground and to 85 grounded battery (not shown). The relay 45 attracts its armature and closes an operating circuit for the slow releasing relay 46, which attracts its armatures to close circuits hereafter described. At the left hand 90 armature and front contact of relay 46, a circuit is closed for actuating the slow releasing relay 47.

95 Simultaneously with the operation of the relay 45, the relay 48 is operated in a circuit closed from grounded battery, winding of this relay, inner left hand back contact and armature of slow releasing relay 49, conductor 50, over the remainder of the circuit in multiple with the relay 42, to ground 100 through the lower winding of relay 26 of Fig. 1. The relay 48 is operated in this circuit and at its left hand armature and front contact closes a circuit which will flash the lamp 51 in a circuit including the interrupter 57. The flashing of the lamp indicates to the B operator that a call is coming to her position and that she should be in readiness to care for the same. At the inner right hand front contact and armature of relay 48, a circuit is closed from 105 grounded battery, over conductor 58, conductor 67, left hand winding of the relay 59 to ground which operates to place a guarding potential temporarily on all idle 110 trunks of the position, so that no other calls can come to this operator's position until she has completed the call which is waiting attention. This is accomplished by the opening of the test circuit at the inner left hand armature and back contact of relay 59. The relay 59 at its outer left hand contact closes a circuit including conductor 68, lower winding of relay 34 of Fig. 1 to grounded battery. Relay 34 attracts its armatures and removes ground potential from the test terminals of idle trunks from the primary switch terminating at this group of secondary switches. All of the trunks out from 115 the secondary switch will be blocked at this 120

time (though not busy) because they all go to this B position which is temporarily engaged.

In the event that all the trunks terminating at the secondary switch are busy, all the relays 42, one of which is individual to each trunk leading from the secondary switch, are operated to remove a short circuit from the upper winding of relay 34 and to close a holding circuit from grounded battery, resistance, front contacts and armatures of relay 42, and upper winding of relay 34 to ground. It will be understood that when any trunk of this group extending from the secondary switch becomes idle, that its associated relay 42 will be de-energized and again short circuits the upper winding of relay 34 so that the primary switch can function again. The group relay 34 of Fig. 1 will also be operated whenever there is no operator at the position under consideration. At this time the relay 69 which is in series with the operator's transmitter circuit is de-energized because the operator on leaving the position will disconnect her telephone set. Relay 69 on de-energizing will extend ground over conductor 68 to operate the relay 34 in the manner previously described.

As soon as the relay 46 attracted its armatures a circuit was closed from ground, inner armature and back contact of relay 55, outer right hand front contact and armature of relay 46, winding of slow releasing relay 54, right hand armature of relay 49 and its back contact, and winding of relay 52 to grounded battery. Relay 52 attracts its armatures and connects the B operator's telephone set to the trunk circuit over which the call is being extended. The B operator thereupon receives the designation of the wanted line and immediately makes her position available to other calls by depressing the position release key 60, or she can proceed to insert her calling plug into the multiple jack of the wanted line after which this operator's position will be automatically made available to other calls.

Two meters 63 and 65 are provided, the first to indicate the number of times that the operator's position is unblocked by depressing the key 60 which is the method that the operator is instructed to follow since it insures more rapid handling of calls, and the second meter 65 shows the total number of calls completed at this position. By comparing the readings on the two meters a supervisor can determine whether the operator is following instructions.

It will be assumed that the operator depresses her position release key 60 to render available her position to succeeding calls. As soon as key 60 is depressed, a circuit is closed from ground, left hand winding of relay 61, right hand winding of relay 61, in

series, outer right hand armature and front contact of relay 48, continuity spring 62 and winding of relay 49 to grounded battery. These relays are energized in this circuit and the relay 61 completes a locking circuit for itself and closes an operating circuit for the meter magnet 63 through its outer left hand front contact and armature, its left hand winding, armature and front contact to ground. Relay 49 on energization closes a locking circuit for itself through its continuity spring 62, its right hand armature and winding of relay 54, outer right hand armature and front contact of relay 46, inner back contact and armature of relay 55 to ground. At the inner left hand armature and back contact of relay 49, the actuating circuit of relay 48 is opened causing this relay to de-energize, and thereby disconnect the lamp 51 from the interrupter and extinguishing the same until the lamp 51 is again lighted at the time of disconnection as will be further described. At the outer left hand armature and back contact of relay 49 a break point is opened in the conductor 58 which would otherwise complete a test circuit at the right hand armature and back contact of relay 48. The opening of this test circuit renders the trunk in use unselectable.

The deenergization of relay 48 also opens at its inner right hand armature and front contact the operating circuit of the relay 59 which has previously been energized to hold the operator's position unselectable.

As soon as the operator received the designation of the wanted line and while the several operations just described have been taking place, she touches the tip of her plug to the sleeve of the wanted line to ascertain whether or not this line is idle. If busy, this last mentioned operation will cause a distinctive click in her headset since the busy condition of the called line will be indicated by battery potential on the sleeve of its jack, and this potential will be extended through the right hand armature and back contact of relay 55 to ground, over conductor 56 which has included therein a coil inductively connected to the operator's receiver.

Let it be assumed that the wanted line is idle in which event the operator will insert her plug P into the jack J of the wanted line. In response to this operation, the sleeve relay 55 will be operated in series with the cut-off relay of the wanted line. These relays are thus energized and attract their armatures. At the right hand armature of relay 55, the test conductor 56 is opened and at the inner left hand armature and front contact of relay 55, a circuit is closed from ground, winding of the relay 64, conductor 70, and winding of the relay 49 to grounded battery. The relay 64 is

energized in this circuit and attracts its armatures. At its inner front contact and lower armature, a circuit is extended from ground at the armature of relay 55, front contact and armature of slow releasing relay 54, winding of the meter magnet 65 to grounded battery. This meter as has been described, registers the number of completed calls. With relay 64 operated, a circuit is closed from the ringing generator, middle armature and contact of relay 47, armature and back contact of relay 71, winding of the trip relay TRIP, front contact and upper armature of relay 64, tip of the plug through substation circuits and bell of the wanted station, ring contact of the jack and plug, inner armature and front contact of relay 64, and resistance to grounded battery. The called party is thus signaled over this circuit and the calling party receives ringing induction through the resistance 72 to inform him that the called party is being signaled. When the called party responds the marginal trip relay operates, and at its armature and front contact short circuits the relay 64 which deenergizes to close a break point in the ring conductor of the trunk in use and also to short circuit resistance 72.

30 The calling subscriber receives talking battery through the windings of relays 160 and 161 while the called party receives talking battery through the windings of relay 71. Relay 71 is energized in this circuit and places a short circuit about the high resistance winding of relay 45 which may have a resistance of 12000 ohms.

When the calling party terminates the call, the answering supervisory signals are lighted in the well known manner, and when the called party replaces his receiver on its switch hook, relay 71 de-energizes and removes the short circuit which exists about the left hand or high resistance winding of relay 45. With this high resistance included in circuit including conductors 43 and 44, the calling supervisory signal is lighted. After receiving these disconnect signals by the lighting of these supervisory lamps the 50 A operator withdraws the plug 7 from the jack of the calling line and the plug 8 of her cord circuit from the jack of the selected trunk. As soon as this takes place, the relay 45 de-energizes and interrupts the operating circuit of the slow releasing relay 46. This last mentioned relay releases and the supervisory lamp 51 of the B operator's position is caused to glow steadily in a circuit extending from grounded battery, lamp 51, left hand armature and back contact of relay 48, outer left hand armature and front contact of relay 55, inner armature and back contact of relay 46 to ground through resistance 81 which may be a pilot relay common to the position. The operator on noting

that lamp 51 is burning steadily knows that the conversation has been completed and removes the plug P from the jack J of the called line. The apparatus at the B operator's position is thereupon restored to its 70 normal position and becomes available in handling a succeeding call.

When the A operator removes her calling plug 8 from the jack 9 of a selected trunk, the relay 10, the circuit of which was controlled through the sleeve of the jack 9 and plug 8 de-energizes and at its inner armature and front contact opens the locking circuit of the switching relay 13. The relay 13 de-energizes to release the trunk finder 75 switch at office #1 and effects the de-energization of relay 19 which has maintained a guarding potential on the trunk whose conductors are designated 17 and 18. The brushes of the trunk finder switch at office 80 #1 remain in engagement with the terminals of the trunk last used, but the brushes of the switch are severed from the conductors of the trunk that terminates therein at the armature and front contacts of the relay 13. 85 The conductors of this trunk are also opened at another point by the removal of the plug 8 from jack 9. The release of the trunk 90 finder switch opens the line conductors extending between office #1 and office #2 with 95 the result that the relay 45 of Fig. 2 de-energizes and retracts its armature. Shortly afterward the slow releasing relay 46 de-energizes, but before the slow releasing relay 47 has had time to retract its armatures, a 100 circuit is closed from ground, armature and back contact of relay 46, inner armature and front contact of relay 47, conductor 50, brush 43, armature and front contact of relay 37, winding of relay 33 to grounded battery, 105 which shunts the relay 26, causing it to retract its armatures. At the upper armatures of relay 26 the brushes of the primary switch are disconnected from the conductors of the trunk that terminate therein, and at the 110 lower armature of this relay its locking circuit is opened. This primary switch after releasing also remains with its brushes in engagement with the terminals of the trunk last used. A short time after the relay 46 115 retracts its armatures, the slow releasing relay 47 de-energizes and opens the circuit which shunted the relay 26 and held energized the relay 33, permitting this relay 33 to retract its armatures. At the outer right 120 hand armature and front contact of relay 33, the locking circuit of the switching relay 37 is opened and this relay retracts its armatures to release the secondary switch whose brushes likewise remain in engagement with the terminals of the trunk last used.

Referring to the modification shown in Figs. 2^A and 3 when the overflow positions one of which is shown in Fig. 3 are em- 130

ployed, each secondary line switch will be provided with one or more sets of overflow terminals indicated at 125, 126, 127 and 162 of Fig. 1 and the regular trunks from these 5 switches, instead of extending only to one operator's position, are distributed among a group of B operators' positions. Furthermore, the group relay 34 of Fig. 1, is made common to a plurality of B operators' positions, instead of being individual to one B position. When this overflow arrangement is used in case all of the B operators' positions, such as shown in Fig. 2 become simultaneously busy, this condition will be indicated by a guarding potential on the test terminals such as 40 of all trunks leading to these positions. Under such conditions if a call is extended to office #2, it will be further extended to overflow positions irrespective of the number of calls awaiting completion at these positions. The method of extending a call when the overflow position arrangement is used, is substantially similar to that previously described.

25 Let it be assumed that a subscriber at A desires to converse with the subscriber at C. The A subscriber will initiate the call by removing his receiver from its switch hook, and this will effect the lighting of the lamp 5 at the A operator's position. The A operator then inserts the plug 7 into the jack 6 and thereafter presses the listening key LK to connect her telephone set to the calling line and to receive the designation of the wanted line. The operator then inserts her plug 8 into the jack 9 of a trunk leading to an idle trunk selecting switch at office #1 and this switch selects an idle trunk leading to a primary switch at office #2 which 40 it is assumed is the wanted office. The primary switch now selects an idle trunk leading to a secondary switch, and since it has been assumed that all of the B operators are busy, this secondary switch will not 45 seize any of the trunks leading to these positions, owing to the busy condition on their test terminals, such as 40 of Fig. 1, but will seize an idle overflow trunk like that shown in Fig. 3 leading to an overflow position.

50 As soon as the test brush 41 of the secondary switch reaches the test terminal 127 of this idle overflow trunk, a circuit is completed for the switching relay 37 extending from grounded battery, resistance, inner 55 right hand armature and contact of relay 33, lower winding of switching relay 37, test brush 41, test terminal 127, test conductor 128, armature and back contact of relay 100, conductor 130, armature and front contact 60 of relay 129 which is energized if this operator is at her position, conductor 131, armature and front contact of relay 132 to ground. It will be noted that his relay 132 is not operated until all the regular B operators' positions are engaged at which time

the relays 59 at these positions will be actuated to remove a short circuit which has previously existed about relay 132.

As soon as the secondary switch has seized the overflow trunk, the conductors 133 and 134 of this trunk will be serially included in a circuit completed through the winding of the supervisory relay 14 at the A operator's position and including both windings of the relay 101 of Fig. 3. The relay 101 is operated in this circuit and at its armature and contact closes an operating circuit for the slow releasing relay 102, and the energization of this relay effects the actuation of the slow releasing relays 103 and 104 for purposes to be described. As soon as the switching relay 37 attracts its armatures, a holding circuit for this relay is closed from grounded battery, upper winding of relay 37, its lower-most front contact and armature, outer-most front contact and armature of relay 33 to ground. Also the holding circuit of the relay 26 is now extended through its high resistance winding, its lower armature and front contact, holding brush 35, inner lower armature and front contact of relay 37, holding brush 43, holding conductor 135, lower winding of relay 100 to grounded battery. The relay 100 is energized in this circuit, and at its upper armature opens the test conductor 128 of the overflow trunk in use and at its lower armature closes a circuit to light the signal lamp 111, to inform the operator that a call is awaiting attention. The circuit for the lamp 111 is traceable from grounded battery, through the lamp, armature and front contact of relay 100, conductor 136, armature and back contact of relay 105, conductor 137, contact 112 of the operator's listening key, contact 113 and the interrupter to ground. Under the control of this interrupter the lamp 111 is flashed to inform the operator that a call is waiting at her position. The operator at the overflow position throws her listening key LK to inductively connect her telephone set shown at the lower right hand corner of Fig. 3, to the trunk conductors 133 and 134 leading to the A operator's position. As in the case where the overflow position is not used, as soon as the secondary switch has seized an idle trunk leading to the overflow position the various tones disappear from the line and the A operator knows that it is time to give the designation of the wanted line. This designation is received by the overflow position operator.

The operator then tests the line leading to the substation at C by touching the tip of the plug P' to the sleeve of the jack J'. This operation connects the sleeve of the jack J' to the operator's headset over conductor 116. If at the time the plug P' is connected to the sleeve of the jack, a guarding potential was present on the sleeve, a distinctive click

will be heard in the operator's headset which informs her that the wanted line is engaged. Let it be assumed that the wanted line is idle, the overflow operator thereupon inserts 5 the plug P' into the jack J' of the wanted line. This operation completes an energizing circuit for the relay 105, closed from grounded battery, upper winding of the relay 100, relay 105, sleeve of the plug P', sleeve 10 of the jack J', through the cut-off relay herein represented as resistance 115 to ground. Relay 105 attracts its armatures and at its left hand armature opens the flashing circuit for the lamp 111 to prevent this 15 lamp from being flashed again on the same call, but at its left hand armature and front contact closes a supervisory circuit in which this lamp will be steadily lighted at the close of conversation as will be described. 20 At the right hand armature and front contact of relay 105, a break point is closed in the conductor 139 of the trunk that terminates in the plug P'. At the outer right hand armature and front contact of relay 25 105, a circuit is closed from ground, conductor 141, winding of relay 106, resistance to grounded battery. Relay 106 is energized in this circuit and attracts its armatures to close a ringing circuit which extends 30 from the ringing generator, conductor 118, inner front contact and armature of relay 103, armature and back contact of relay 109, winding of trip relay 108, upper front contact and armature of relay 106, tip of 35 plug P', through the substation circuits and bell of the substation C, ring of the jack J', ring of the plug P', inner upper armature and front contact of relay 106, resistance to grounded battery. The resistance 40 120 causes a tone to be transmitted to the subscriber at A to indicate that his party is being signaled. As soon as relays 105 and 106 are actuated an operating circuit is closed from grounded battery, winding of 45 meter magnet 107, inner front contact and armature of relay 104, armatures and front contacts of relays 106 and 105 to ground. This meter indicates the number of calls completed at this overflow position. When 50 the called subscriber at C answers, the trip relay 108 attracts its armature which places a short circuit from grounded battery, resistance, armature and contact of relay 108, outer right hand contact and armature of 55 relay 105 to ground about the relay 106. Relay 106 thereupon deenergizes and retracts its armatures. As soon as this takes place a circuit is completed for the relay 109 serially including both of its windings 60 and the conductors 139 and 140. With relay 109 operated the ringing circuit previously described is interrupted to prevent the re-application of ringing current to the wanted line during the call just completed. At the 65 left hand armature and front contact of relay 109, the high resistance left hand winding of the relay 101 is eliminated from the circuit including the conductors 133 and 134 to control the supervisory means associated with the A operator's cord circuit. 70 When the calling subscriber at A and the called subscriber at C terminate the connection, the answering and calling supervisory lamps (not shown) of the A operator's cord circuit are lighted in a manner previously 75 described to indicate to her that the call has terminated. She thereupon removes the plugs 7 and 8 of her cord circuit from the jacks with which they were in engagement. This causes relay 10 to de-energize and 80 interrupt the holding circuit of the switching relay 13. This relay deenergizes and interrupts the holding circuit of the relay 19, which removes the guarding condition from the test terminal of the trunk that has just 85 been in use. With the conductors 133 and 134 opened, relay 101 retracts its armature and after a short interval the relay 102 retracts its armatures. This effects the steady lighting of lamp 111 at the overflow operator's position in a circuit completed from grounded battery, lamp 111, armature and front contact of relay 100, conductor 136, left hand armature and front contact of 90 relay 105, inner armature and back contact of relay 102, the winding of pilot relay to ground. The lighting of this lamp informs the operator that the connection has been 95 terminated and she removes the plug P' from the jack J' with which it has been in engagement. 100

The trunk just used of the overflow position is not in condition to receive another call until the relay 100 deenergizes. This occurs when the B operator at the overflow 105 position removes the plug P' from jack J' after the A operator has released her cord circuit. It will be understood that the energizing circuit of the upper winding of relay 100 is broken at the plug P'. 110

At the time that the A operator releases her cord circuit, relay 102 de-energizes while the slow releasing relay 103 is for a short time held operated. This places a ground potential on conductor 135 through the outer front contact and armature of relay 103, and the left hand armature of relay 102 to short circuit and release relay 26. Relay 26 controls the release of the primary and secondary switches. With these switches released 115 the energizing circuit for the lower winding of relay 100 is interrupted. The apparatus and circuits are now in condition to receive a second call. 120

In Figs. 2, 2^A and 3 there are provided 125 release relays 164 and 166 and release keys 165 and 167. It will only be necessary to explain the function and operation of the release relay 164 and release key 165, since the function of relay 166 and key 167 are 130

identical therewith. These relays and release keys are provided to care for the condition that arises when the A operator momentarily inserts the plug 8 into the jack 9, and then removes this plug from its jack. Under this condition the line switch at office #1 seizes a primary line switch and this in turn seizes a secondary line switch at the second office. The primary and secondary switches at office #2 will remain operated, and the supervisory lamp 51 will continue to flash. If some means like the release relay 164 and key 165 were not provided, it would be impossible to release the primary and secondary switches operated in this way. When an occasion arises similar to that just described, the B operator on connecting her telephone set to the trunk designated by the lamp 51 and on discovering that the call has been abandoned inserts the plug P into the jack associated with the release relay 164. This energizes relay 164 and causes it to attract its armature. The operator then depresses key 165 and connects ground to the release trunk 50, and this effects the release of the primary switches as in the case of a normal call.

What I claim is:

1. In an automatic telephone system, a plurality of incoming lines, primary trunk selecting switches for said lines, each switch being provided with movable brushes including a test brush and a holding brush, contacts for each switch arranged to be engaged by its brushes, primary trunks terminating in the contacts of said primary switches, each trunk having a test conductor and a holding conductor, means for characterizing the test conductors of selectable trunks by the presence of potential and for characterizing unselectable trunks by the absence of potential, means for operating the brushes of the primary line switch of an incoming circuit to move its brushes over the contacts of said primary trunks, means responsive to the engagement of the test conductor of a selectable trunk for stopping said primary trunk selecting switch, a holding circuit thereupon completed including the holding conductor of the selected trunk for holding said primary line switch in its operated condition, a secondary switch in which each primary trunk terminates, secondary trunks terminating in said secondary switches, means for characterizing selectable secondary trunks by the presence of potential and for characterizing unselectable trunks by the absence of potential, and means responsive to the seizure of a primary trunk by the primary line switch for causing the secondary switch to seize a secondary trunk distinguished by the presence of potential.

2. In an automatic telephone system, a

plurality of incoming lines, primary trunk selecting switches for said lines, each switch being provided with movable brushes including a test brush and a holding brush, contacts for each primary switch, to be engaged by the various brushes, primary trunks terminating in the contacts of said primary switches, each trunk having a test conductor and a holding conductor, means for characterizing the test conductors of selectable trunks by the presence of potential and for characterizing the test conductors of unselectable trunks by the absence of potential, means for operating the brushes of the primary line switch of an incoming circuit to move its brushes over said primary trunks, means responsive to the engagement of the test conductor of a selectable trunk by its test brush for stopping said primary switch, a holding circuit thereupon completed through the holding brush of said primary switch including the holding conductor of the selected trunk for holding said primary line switch in operated condition, a secondary line switch in which each primary trunk terminates, secondary trunks terminating in said secondary line switches and means responsive to the seizure of a primary trunk by a primary switch for causing the secondary line switch to seize an idle secondary trunk.

3. In an automatic telephone system, a plurality of incoming lines, a plurality of primary trunks terminating in said primary trunk selecting switches, means for characterizing unselectable primary trunks by the absence of potential and for characterizing selectable trunks by the presence of potential, means for operating a primary trunk selecting switch of an incoming line to select a primary trunk characterized by the presence of potential, a secondary trunk selecting switch for each primary trunk, secondary trunks terminating in said secondary switches, means for operating the secondary switch of the selected trunk to seize an idle secondary trunk and means for preventing the selection of a primary trunk when all the secondary trunks are in an unselectable condition.

4. In an automatic telephone system, a plurality of incoming lines, primary trunk selecting switches for said lines, a group of primary trunks terminating in said primary trunk selecting switches, means for characterizing unselectable primary trunks by the absence of potential and for characterizing selectable trunks by the presence of potential, said means including a relay common to said group of primary trunks, said relay being provided with sets of contacts less in number than the number of primary trunks in said group, means for operating the primary trunk selecting switch of an incom-

ing line to select a primary trunk characterized by the absence of potential, a secondary switch for each primary trunk, a group of secondary trunks terminating in said secondary switches, means for operating the secondary switch of the selected trunk to seize an idle secondary trunk and means effective when all the group of secondary trunks are in an unselectable condition for causing said relay to characterize all of said primary trunks as unselectable.

5. In an automatic telephone system, incoming lines, primary trunk selecting switches for said lines, a group of primary trunks terminating in said primary trunk selecting switches, means for characterizing unselectable primary trunks by the absence of potential and for characterizing selectable trunks by the presence of potential, said 10 means including a relay common to said group of primary trunks, means for operating the primary switch of an incoming line to select a primary trunk characterized by the presence of potential, a secondary trunk 15 selecting switch for each primary trunk, secondary trunks terminating in said secondary switches, means for operating the secondary switch of a selected primary trunk to seize an idle secondary trunk, a relay for each secondary 20 trunk arranged to be operated when its associated trunk is seized, and means for disabling the operating means of the common relay when any of the secondary trunks are 25 in an inert condition.

30 6. In an automatic telephone system, incoming lines, primary trunk selecting switches for said lines, a group of primary trunks terminating in said primary trunk selecting switches, means including a test 35 conductor for each primary trunk for characterizing unselectable primary trunks by the absence of potential and for characterizing selectable trunks by the presence of potential, a relay common to said group of primary trunks, said relay when operated removing potential from the test conductors of the group of primary trunks, means for operating the primary switch of an incoming line to select a primary trunk characterized by the presence of potential, a secondary trunk selecting switch for each primary trunk, secondary trunks terminating in said secondary switches, means for operating the secondary switch of the selected 45 primary trunk to seize an idle secondary trunk, a relay for each secondary trunk arranged to be operated when its associated trunk is seized, and means for disabling the common relay when any of the relays of the 50 secondary trunks are in an inert condition.

55 7. In an automatic telephone system, incoming lines, primary trunk selecting switches for said lines, a group of primary trunks terminating in said primary trunk

selecting switches, means for characterizing unselectable primary trunks by the absence of potential and for characterizing selectable trunks by the presence of potential, said means including a relay common to said group of primary trunks, means for operating said relay to remove potential from the primary group of trunks, means for operating the primary switch of an incoming line to select a primary trunk characterized by the presence of potential, a secondary switch 65 for each primary trunk, secondary trunks terminating in said secondary switches, means for operating the secondary switch of a selected primary trunk to seize an idle secondary trunk, a relay for each secondary 70 trunk arranged to be operated when its associated trunk is seized, and means for disabling the operating means of the common relay when any of the secondary trunks are 75 in an inert condition.

8. In an automatic telephone system, a plurality of incoming lines, primary trunk selecting switches for said incoming lines, means for characterizing selectable trunks by the presence of potential and for characterizing unselectable primary trunks by the absence of potential, means for operating the primary switch of an incoming line to select a primary trunk characterized by the presence of potential, a secondary trunk selecting switch for each of said trunks, a second set of trunks accessible to said secondary trunk selecting switches, said secondary set of trunks including one or more over-flow trunks, and means preventing the seizure of 80 the over-flow trunks when the remaining secondary trunks are idle.

9. In an automatic telephone system, a plurality of incoming lines, primary switches for said incoming lines, each switch having sets of contacts and brushes including a test brush for engaging said contacts, primary trunks terminating in said contacts, each primary trunk having a test conductor terminating in one of said contacts, operating 105 means for advancing said brushes over said sets of contacts to seize a selectable primary trunk, a relay common to said primary trunks for normally applying potential to the test conductors of said primary trunks to render them selectable, means for removing said potential from the test conductor of a selected primary trunk, a secondary switch for each primary trunk, secondary trunks terminating in said secondary switches, 110 means for operating said secondary switches to seize a selectable secondary trunk, a relay for each secondary trunk arranged to be operated on the selection of its associated trunk, and means effective on the operation of all of the relays of the secondary trunks for operating said common relay.

10. In a telephone system, incoming lines,

a plurality of operators' positions, means including automatic switches for extending said incoming lines to said operators' positions, a plurality of recording devices at each operator's position, means for rendering an operator's position unselectable, two releasing means for rendering said operator's position

selectable, and means including said recording devices for determining which releasing means has been employed.

In witness whereof, I hereunto subscribe my name this 29th day of March, A. D. 1920.

WINFRED T. POWELL.
